UNITED STATES PATENT OFFICE

LUTHER D. LOVEKIN, OF ARDMORE, PENNSYLVANIA, ASSIGNOR TO KITSON COMPANY, OF PHILADELPHIA, PENNSYLVANIA, A CORPORATION OF WEST VIRGINIA

EMERGENCY CARTRIDGE-TYPE SHUT-OFF VALVE

Application filed October 13, 1927. Serial No. 225,943.

My invention relates to thermostatically released shut-off valves for cutting off the fuel supply to a boiler or other container of liquid heated by the combustion of the fuel.

6 The main purpose of my invention is to provide a readily removable and replaceable cartridge for holding parts in spring-pressed open position so that softening of metal in the cartridge will permit the spring to act to close the fuel valve.

10 A further purpose is to provide a readily removable cartridge complete in itself, containing a fusible material and adapted to hold the fuel valve in open position against the pressure of a spring and at the same time to guide the parts in closing movement.

15 A further purpose is to provide a pocket within a valve-supporting body, to utilize a cartridge within the pocket comprising a holding device and fusible material, and to restrain the valve against spring-pressed closure by a pin adapted to punch the fusible material when the material softens without 20 waiting for it to melt.

25 A further purpose is to provide a spring-pressed fuel valve closure adapted to be released by reason of the heating of a fusible material, with a guide at each end and a non-circular section for use in oscillating the valve for the purpose of grinding the valve on to its seat.

30 A further purpose is to provide novel mounting means for a valve upon a stem and a fusible disc within a pocket.

35 Further purposes will appear in the specification and in the claims.

40 I prefer to illustrate my invention by one form only, appearing in two slightly varying constructions, among the many in which it may appear, selecting a form which is practical, efficient, reliable and inexpensive, and which at the same time well illustrates the principles involved.

45 Figure 1 is a central longitudinal section through my valve and a fitting in which it may be supported.

50 Figure 2 is a reduced side elevation of the valve seen in Figure 1.

55 Figure 3 is a reduced section correspond-

ing to Figure 1, showing the valve only, and illustrating a slight modification.

Figures 4 and 5 are reduced side elevations illustrating two of the locations in which the valve may be placed.

60 In the drawing similar numerals indicate like parts.

Describing in illustration and not in limitation and referring to the drawings:

65 My thermostatically operated shut-off valve comprises a support 6 threaded at its lower end at 7 for intimate contact with any boiler 8, or for connection to any member adapted to receive and communicate the temperature of the heating liquid (here treated as water) to the support 6.

70 Upon the support is mounted a valve 9 here shown as a globe valve and having its valve seat 10 axially in line with the support.

75 The fuel ordinarily considered is gas, but it may be liquid, and passes through the valve from pipe 11 to pipe 12 when the valve is open as in the figure.

80 Within the support and in close proximity to the fitting, boiler or other device upon which my automatic shut-off valve is mounted, I install a cartridge comprising an outer shell 13, a fusible element 14 (shown as a flat disc in Figure 1 and as in inverted cup in Figure 2) and a sleeve 15 which holds the fusible element in place and at the same time performs guiding functions for a valve spindle 16.

85 The sleeve 15 is threaded into the top of the shell 13 and is provided with an external thread at 17 to permit removal of the entire cartridge by means of a correspondingly threaded socket inserted from above. The end of the socket engaging portion of the sleeve is radially slotted.

90 The outside of the shell is preferably provided with a slight upward flare so as to make it more easy to withdraw the shell from its recess seat 18. The recess is tapered also.

95 The spindle 16 carries a valve disc 20 above the valve seat 10 and the valve is spring-pressed toward closure by a barrel spring 21 compressed between the valve and the end 100

wall of a recess 22 in a cap member 23 screwed into the valve body at 24.

The interior of the cap forms a cylindrical loose guide at 25 for a cylindrical outwardly directed skirt 26 upon the outer side of the valve 20.

The valve is thus loosely guided below by locating the lower end of the stem within the bore of the sleeve 15, and above by the skirt 26 within the cylinder 25.

For convenience of manufacture so that valve and skirt, if desired, may be made separate from the stem, I have shown the stem as provided with a boss 27 which the valve 15 engages, and have provided a portion of the stem above the valve with a section larger than that of the stem extension 28, which portion is threaded to receive a nut 29. The nut is shown as locked by pin 30.

29 The stem extension 28 is slotted at 31 to provide easy hold for a suitable tool for grinding the valve to its seat.

In operation the parts are put in place as shown and the valve remains open with the 25 spring 21 under compression during normal operation of the burner, the fusible element being heated by conduction from the metal portion 8 of the boiler through the metal support 6 and shell 13, and the heat from the 30 water of the boiler. It will be evident that the heat conducted whether through the shell or directly from the water is all of it the heat from the excessively highly heated water within the boiler.

35 If the heating liquid becomes excessively hot, the fusible element 14 softens to a point where it is no longer able to support lower stem 16 against the pressure of the spring 21 and the stem 16 is driven through the disc, 40 closing the valve.

The valve remains closed until the cap 23 is removed, when a new fusible element is put in place and the valve reset.

The replacing of the fusible element requires removal of the cap and removal of the cartridge in its entirety from the body of the valve, removal of the sleeve 15 from the cartridge shell 13 and replacing of the fusible element 14 with a new one, with subsequent 50 reassembly of the different parts with the body of the valve.

I show in Figure 3 minor differences of detail from that of Figure 1.

The cap 23' is extended upwardly a sufficient distance to permit the stem 28' to extend well beyond the body of the valve, the shell 13' carrying the fusible element is placed closer to the outer end of the shank support 7, and the inverted cup form of fusible element at the bottom of the shell is used instead of the flat disc element of Figure 1. A further detail difference lies in making the sleeve 15' of uniform diameter throughout its length instead of making the upper 65 portion of the sleeve of reduced diameter, as

in Figure 1, which may in some cases be advantageous in permitting the use of a smaller socket when removing the cartridge.

In Figure 1 the fusible element 14 rests upon a shoulder 32 formed by counterboring the upper end of the sleeve 13, an arrangement that gives considerable room below the fusible element for the downward movement of the stem during valve closure, while in Figure 3 the space for movement of the stem is provided by making the fusible element in the form of an inverted cup which, resting upon the bottom of the shell 13', brings the fusible element closer to the source of heat.

The valve 20' and the stem are integral, 80 avoiding the necessity for the boss 27 and the holding mechanism by which the stem and valve are united in Figure 1.

The construction is unusually compact, 85 may be quickly and easily reset without interference with the fuel or water connections beyond shutting off the fuel supply, and has been found to be remarkably uniform in the temperature at which it operates, as the 90 spring may easily be made strong enough to punch the fusible element at the first sign of softening of the element, and the temperature of softening of the material is substantially uniform.

95 In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention what I claim as new and desire to secure by Letters Patent is:—

100 1. In a fuel cut-off valve for insertion in the fuel supply line to a boiler, a globe valve body, an extension integral therewith, a disc valve in the body, spring-pressed toward closure, a fusible element inside the extension supporting the disc valve from closure and connections between the boiler and the element adapting the element to heat by conduction from the heat of the water in the boiler and to soften for operation of the cut-off when the boiler temperature becomes undesirably high.

105 2. In a fuel cut-off valve for insertion in the fuel supply line to a boiler, a body having a lateral opening, inlet and outlet compartments and a laterally extending shank for heat conducting connection to a boiler, in combination with a valve assembly insertable and removable at said opening and including a valve and a fusible element having heat conducting connection with the shank whereby it is heated by the excessive heat of the water in the boiler and controls the operation of the valve.

3. In a fuel cut-off valve for insertion in the fuel supply line to a boiler, a body having a lateral opening, inlet and outlet compartments and a laterally extending shank for heat conducting connection to a boiler, in combination with a valve assembly insertable and removable at said opening and including a valve and a fusible element mounted inside the shank in heat conducting connection with the shank and controlling the operation of the valve. 70
4. In a fuel cut-off valve for insertion in the fuel supply line to a boiler, a body having a lateral opening, inlet and outlet compartments and a laterally extending shank for heat conducting connection to a boiler in combination with a valve assembly insertable and removable at said opening and including a valve stem, a valve mounted thereon spring-pressed toward closure, a cartridge seating in the shank and guiding the stem, and a heat element inside the cartridge, supporting the stem in valve open position and controlling the operation of the valve by an adaptation to fail if subjected to undesirably high temperature. 75
5. In a fuel cut-off valve for insertion in the fuel supply line to a boiler, a body having a lateral opening, inlet and outlet compartments and a laterally extending shank for heat conducting connection to a boiler in combination with a valve assembly insertable and removable at said opening and including a valve stem, a valve mounted thereon spring-pressed toward closure, a cup-shaped metal container seating in the shank, a sleeve threaded into the open end of the cup guiding one end of the stem and presenting a threaded end outside of the cup for use in withdrawing the cup by means of a threaded socket. 80
8. In a fuel cut-off valve for insertion in the fuel supply line to a boiler, a body having a lateral opening, inlet and outlet compartments and a laterally extending shank for heat conducting connection to a boiler in combination with a valve assembly insertable and removable at said opening and including a valve stem, a valve mounted thereon, spring-pressed toward closure, a cup-shaped metal container seating in the shank, a fusible element in the container adapted to hold the valve normally open and a sleeve threaded into the open end of the cup guiding one end of the stem and presenting a threaded plug which is radially slotted for tool engagement. 85
9. In a fuel cut-off valve for insertion in the fuel supply line to a boiler, a globe valve body having a partition wall between inlet and outlet compartments, and a valve seat around a perforation in the wall and a side opening into one of the compartments in line with the perforation, in combination with a disc valve adapted to close upon the seat, having a stem extending through the perforation and removable through the opening, a cartridge in the other compartment including a fusible element, and removable through the perforation and through the opening, the fusible element being adapted to engage the valve and hold the valve away from its seat, a cap closing the opening, a spring compressed between the disc and the cap and connections between the element and the boiler adapting the element to heat by conduction from the boiler and to soften when the heater temperature becomes undesirably high. 95
10. In a fuel cut-off valve for insertion in the fuel supply line to a boiler, a body having a lateral opening, inlet and outlet compartments and a laterally extending shank for heat conducting connection to a boiler, in combination with a valve assembly insertable and removable at said opening and including a valve stem, a valve mounted thereon, spring-pressed toward closure, a cartridge seating in the shank and guiding the stem, and a disc heat element inside the cartridge, supporting the stem in valve open position and controlling the operation of the 100

- 115
- 120
- 125
- 130

valve by an adaptation to fail if subjected to undesirably high temperature.

11. In a fuel cut-off valve for insertion in the fuel supply line to a heater, a body having 5 a lateral opening, inlet and outlet compartments and a laterally extending shank for heat conducting connection to a boiler, in combination with a valve assembly insertable and removable at said opening and including 10 a valve stem, a valve mounted thereon and a heat element compressed by said stem in movement of the valve toward closing and adapted to soften and permit such closing movement when subjected to undesirable 15 high temperature.
